INVENTOR

Louis Sharkey
C. P. Goepel.

his ATTORNEY

UNITED STATES PATENT OFFICE.

LOUIS SHARKEY, OF BROOKLYN, NEW YORK.

WINDOW-SHADE MOUNTING.

Application filed April 17, 1923. Serial No. 632,594.

To all whom it may concern:

Be it known that I, LOUIS SHARKEY, a citizen of the United States, and resident of Bath Beach, borough of Brooklyn, county 5 of Kings, and State of New York, have invented new and useful Improvements in Window-Shade Mountings, of which the following is a specification.

This invention relates to means for detachably mounting a window shade upon a window casing, and has for its main object 10 to provide a device of the character stated whereby a window shade holder may be detachably and adjustably mounted upon a window frame, vertically thereof, so that the lower portion of the shade may be brought down to the lower portion of windows of various heights.

A further object of the invention is to 20 provide means for accomplishing such a result that shall be simple in construction, effective in operation, durable in use, and in which the parts are not liable to become disarranged from their working position.

With the foregoing and other objects in view, hereinafter stated, the invention consists in the novel construction, combination, and arrangement of parts hereinafter more 30 specifically stated, and illustrated in the accompanying drawings, wherein is shown a device embodying the structure of the invention in its preferred form, but it is to be understood that changes, variations, and modifications may be resorted to without departing from the scope of the invention.

In describing the invention in detail, reference is had to the accompanying drawings, which form a part of this specification, and wherein like characters of reference 40 indicate corresponding parts throughout the several views and wherein:

Fig. 1 represents in side elevation a window shade, partly in section, and a holder mounted upon a window casing;

Fig. 2 is a side elevation taken on the line 2—2 of Fig. 1;

Fig. 3 is a horizontal section taken on the line 3—3 of Fig. 1;

Fig. 4 is a perspective view of a side bar 50 upon which the ends of the shade holder are mounted;

Fig. 5 is a perspective view of a clip adapted to hold one end extension of a shade holder; and

Fig. 6 is a perspective view of a clip 55 adapted to hold the other end extension thereof.

As illustrated in the drawings, shade supporting bars 1 are mounted in any suitable manner upon the sides of a window frame 2. These side bars are made of bendable material such as sheet metal, so as to be reversely doubled over on themselves, the inner member or base 3 of which may be of any desired formation, provided with apertures adapted to engage studs or screws by means of which the bars may be secured to a window casing.

In the drawings, the inner member 3 is shown extending beyond the other members 70 of the side bars. That is not an essential feature of the invention, however, and if desired the inner member 3 may be of the same width, or of a lesser width than the remaining members and be secured to the casing in any suitable manner.

The outer member 4 of the side bar is recessed longitudinally on its margin 5 and provided with notches 6 for retaining therein 80 clips supporting the ends of the shade roller. The recesses are of a width adapted to receive the inturned end of one member 7 of a clip, and are preferably provided with inclined upper margins 8 whereby that portion of the clip may be readily placed within 85 said recesses.

The supporting clip is preferably comprised of oppositely disposed members 7 and 9 doubled over on themselves at one end, and provided at the doubled-over end with an 90 aperture adapted to hold the extension of the end of a shade roller.

One aperture 10 is made rectangular to receive the flat end of a roller, as shown in Fig. 5, while the doubled end of the opposite 95 clip is provided with a round aperture 11, as shown in Fig. 6.

The rectangular aperture 10 is shown in Fig. 5 as surrounded by portions of the clip member. If desired, however, the upper portion 12 of said member above the aperture 10 may be cut away, forming in that end of the clip a recess adapted to receive the flattened end of a shade roller.

The members 7 and 9 of the clip are offset 105 from each other at their outer ends, and the member 7 is provided with an inturned lip 13 and an offset lip 14. When the clip is

in position on the side bars, the outer fold and the intermediate fold of said bar are engaged between the offset members of said clip, as shown in Fig. 3, the inturned lip 13 5 engaging the outer member 4 of the side bar and the offset lip 14 resting within the notches 6 of the side bar, as shown in Figs. 2 and 3.

By means of such construction, the clip 10 is firmly held by the outer fold 4 and the intermediate fold of said side bar against rocking or torsional movement. The offset portion 15 of one of the members of said clip by bearing against the inner margin 15 of the outer fold of the side bar and the inturned lip 13 by engaging the outer margin of the member 4 of the side bar, likewise prevent torsional movement of the clips.

20 A stop 16 of any desired construction may be provided on the side bars to prevent the clips from being removed from the side bars.

When the device is in use, the roller may 25 be supported at any desired height on a window frame within the limits of the length of the shade; and the lower portion of the shade may be brought down to the bottom of the window frame, irrespective 30 of the height of the window relative to the length of the shade.

In addition thereto, a window shade of a given length may be mounted upon a window frame at different heights thereon, 35 by removing the clips from one set of recesses and notches to another set on the window casing, thereby enabling any desired portion of the window to be shaded, and any desired portion of the window 40 above the shade to be exposed.

For most purposes I prefer to support the flat end of the shade roller within an angular aperture, such as indicated by 10 in Fig. 5, rather than by means of an open 45 slot formed in that end of the member. By means of such construction that end of the roller shade is held firmly in place.

What I claim as new and desire to secure by Letters Patent is:

50 1. The combination with a window shade roller, of a side bar doubled on itself to provide three members, the outer member having marginal recesses, said recesses having notches at one end thereof, and a clip 55 engaging an end of said roller and the notches of said recesses.

2. In combination with a window shade roller, a side bar comprising a fastening

member, an intermediate member and an outer member, said outer member having 60 marginal recesses with notches in the lower parts of the recesses, and a clip doubled on itself and having a recess adapted to support one end of said roller, the free ends 65 of the clip adapted to slidably embrace the intermediate and outer member of the side bar, said clip having at one of its free ends an inturned portion engaging the recessed edge of the outer member of said side bar, said clip also having at one free end thereof 70 an offset lip adapted to engage the notches of the outer member of the side bar.

3. The combination with a window shade roller, of a side bar doubled on itself to 75 provide three members and a stop, the inner member adapted to receive a fastening for supporting the side bar, the outer member provided with marginal recesses having notches at their lower portions, and a clip having an open end for detachably 80 engaging an end of said roller, said clip having an offset lip adapted to engage said notches, said clip having a slidably engagement with said side bar limited by said 85 stop.

4. The combination with a window shade roller, of a side bar doubled on itself to 90 provide three members, the inner member adapted to receive a fastening to support the side bar, the outer member having marginal recesses with notches in the recesses, and a clip comprising a piece of sheet material folded on itself to provide two members, said members having an aperture to receive an end of the roller, one member 95 of said clip being offset from the other member forming a fork adapted to engage the outer and intermediate members of said side bar, one member of said clip having means for engaging the notches of said side 100 bar.

5. In a device of the character described, for use in combination with a window shade roller and supporting side bars, a twofold clip doubled over on itself at one end and 105 provided with an aperture extending therethrough, one of the members of said clip having an inturned portion, and an offset lip, the other member being offset from the first named member and arranged in part 110 substantially parallel therewith.

In testimony that I claim the foregoing as my invention, I have signed my name hereunder.

LOUIS SHARKEY.
